The ornamental design for a flask for a cosmetic product, as shown and described.

DESCRIPTION

FIG. 1 is a perspective top, front and left side view of a flask for a cosmetic product including a top according to the present invention.

FIG. 2 is front view of the flask for a cosmetic product depicted in FIG. 1, the rear view being a mirror image thereof.

FIG. 3 is a left side view of the flask for a cosmetic product depicted in FIG. 1, the right side view being a mirror image thereof.

FIG. 4 is front view of the flask for a cosmetic product depicted in FIG. 1, but with the top removed to disclose the underlying parts.

FIG. 5 is an enlarged scale top view of the flask for a cosmetic product as depicted in FIG. 4.

FIG. 6 is right side view of the flask for a cosmetic product as depicted in FIG. 4, the left side view being a mirror image thereof; and,

FIG. 7 is a rear view of the flask for a cosmetic product as depicted in FIG. 4.
